DESIGN FOR A CANDLE HOLDER

Ralph A. Ajello, New York, N. Y.

Application February 26, 1945, Serial No. 118,133

Term of patent 7 years

(Cl. D48—2)

To all whom it may concern:

Be it known that I, Ralph A. Ajello, a citizen of the United States of America, residing at 733 East 232d Street, in the county of Bronx and State of New York, have invented a new and original Design for a Candle Holder, of which the following is a specification, reference being had to the accompanying drawing, forming part thereof, and in which:

I claim:

The ornamental design for a candle holder, as shown.

RALPH A. AJELLO.
